BASEBALL BAT

John F. Dunn, Santi Pierini, and Robert Turner,
all of Dos Palos, Calif.

Application July 6, 1959, Serial No. 56,669

Term of patent 3½ years

(Cl. D34—5)

Figure 1 is a front elevational view showing a baseball bat incorporating our new design;

Figure 2 is a side elevational view thereof;

Figure 3 is an end view thereof, from the left end of Figure 2.

The dominant feature of my design resides in the portion shown in full lines.

We claim:

The ornamental design for a baseball bat, substantially as shown and described.
